APPARATUS FOR ASSEMBLING PERCUSSION PRIMERS

Sidney E. Van Tuyl, Riverside, Ill., assignor to
American Tag Company, Chicago, Ill., a corporation of Illinois

Application June 10, 1942, Serial No. 446,519

16 Claims. (Cl. 86—1)

This invention relates to apparatus for assembling percussion primers and more particularly to a machine for assembling liner tubes and diaphragms in primer bodies.

It has heretofore been the practice in assembling percussion primers to roll sheets of paper or the like into tubes by hand and force them into the primer bodies by a hand operation. Thereafter diaphragms also formed of paper or the like have been forced into the primer bodies in an effort to provide a seal in the intermediate portion of the bodies. This operation being substantially entirely handwork has been slow and tedious as well as expensive.

In my copending application, Serial No. 443,710 filed May 20, 1942, I have disclosed and claimed a liner for percussion primers which is preformed and carries as a part thereof a sealing diaphragm. By the use of this construction the assembly operation is substantially speeded and a great deal of hand labor previously required is eliminated.

The present invention has for one of its objects the provision of a machine for assembling liners in primer bodies by which the operation can be greatly speeded with the elimination of substantially all handwork.

Another object of the invention is to provide apparatus for assembling percussion primers in which the several operations are performed automatically.

Still another object of the invention is to provide apparatus for assembling percussion primers in which the liner is assembled in the primer body and sealing material is applied to the upper end of the liner.

A further object of the invention is to provide apparatus for assembling percussion primers in which the sealing material is uniformly distributed around the periphery of the diaphragm in the primer body. According to one feature of the invention, the primer bodies are held at an angle to the horizontal and are rotated in order to flow the sealing material around the periphery of the diaphragm.

A still further object of the invention is to provide apparatus for assembling percussion primers in which the several operations are performed by fluid pressure under the control of a master control valve.

The above and other objects and advantages of the invention will be apparent from the following description when read in connection with the accompanying drawings, in which—

Figure 1 is a side elevation of a machine embodying the invention;

Figure 2 is a diagram illustrating the operating cycle;

Figure 3 is a partial section on the line 3—3 of Figure 1;

Figures 4 and 5 are enlarged partial sections illustrating application of the sealing material; and

Figures 6, 7 and 8 are sectional views illustrating the several steps in the assembly operation.

10 The machine of Figure 1 comprises a frame 10 formed of beams or the like supported at an angle to the horizontal on a base 11 by means of posts 12. A conveyor supplies primer bodies to the frame and is illustrated as being formed by a chain 13 having a plurality of supporting brackets 14 thereon to receive the primer bodies illustrated at 15. As shown, two such chains are provided extending transversely across the frame and supporting the primer bodies 15 at 15 the same angle as the frame. At the side of the frame from which the primer bodies leave, bars 16 are supported between the chains upon which the primer bodies will rest so that the bodies will be rotated when moving away from the frame 25 for a purpose to appear later.

Liner tubes are supplied to the frame by means of a chute 17 having an off-set lower portion 18 from which the liners are adapted to be fed by fingers 19. Normally the liners will remain in a vertical stack in the chute 17 until the fingers 30 19 move in to displace the lower-most liner so that it can drop through the off-set portion 18 into a trough 21 on the frame. The fingers 19 are adapted to be operated by a fluid motor 22 shown as comprising a cylinder and piston to reciprocate the fingers.

The primer bodies and liners are fed into register with a guiding and locating head 23 fixedly supported on the frame. As best seen in Figures 40 6 to 8, the head is formed with a cylindrical bore 24 having an enlarged seat portion 25 at one end to receive the open end of the tubular primer body. Preferably a conical tapered inward end is provided to guide the primer body into the seat. At the opposite end a similar conical tapered portion 27 is provided in the head to guide the liner tubes as shown at 28 into the opening 24.

The liner tubes are adapted to be forced into 50 the primer body by means of a plunger 29 aligned with the opening 24 and carried by a block 31 which is slidable on the frame 10. A stop pin 32 may be inserted in any one of a series of openings 33 in the frame to limit forward movement 55 of the block thereby to adapt the machine quick-

ly and easily to the handling of liners of different lengths.

The block 31 is adapted to be reciprocated on the frame by a fluid motor 34 shown as comprising an elongated cylinder secured to the frame and carrying a piston connected by a piston rod 35 to the block. The primer bodies are adapted to be forced into the opposite end of the head 23 to seat at 25 by means of a similar fluid motor 36 secured to the frame and having its piston carrying a head 37 to engage the lower end of the primer body.

The liner tubes 28 illustrated herein are of the type more particularly described and claimed in my copending application, Serial No. 443,710 filed May 20, 1942, and comprise a tubular body of paper or the like sealed at one end by a relatively flat diaphragm 38 coated with sealing material 39. After these liners are assembled in the primer bodies it is desirable that a relatively small quantity of sealing material should be injected around the periphery of the diaphragm to insure that it will seal tightly against the walls of the primer body. For this purpose the plunger 29 is made hollow as best seen in Figures 4 and 5 and is formed at its forward end with a reduced cylinder 41 communicating with outlet passages 42 which terminate adjacent the periphery of the plunger. A small plunger or piston 43 is reciprocable in the plunger 29 and is adapted to enter the cylindrical portion 41 to force a measured charge of sealing material therefrom through the outlet openings 42. The plunger 29 is kept full of sealing material at all times from any suitable supply through a flexible conduit 44 connected with the head 31 and through the head with the interior of the plunger.

The piston 43 is reciprocated by a fluid motor 45 comprising a cylinder carried by a bracket 46 on the head 31 and having its piston directly connected to the piston 43. This motor will reciprocate with the head and will, when energized, cause the piston 43 to enter the cylinder 41 and force a measured charge of sealing material therefrom. This operation is shown in Figures 4 and 5, Figure 5 illustrating how the sealing material is forced through the passages 42 around the periphery of the diaphragm 38.

The machine is operated by a motor shown as an electric motor 47 secured to the frame 10 and which may run constantly during operation of the machine. The motor operates through a speed reducer 48 to drive a control valve 49. This valve is not shown in detail but is preferably a rotary type valve having a series of ports therein to establish communication with the several fluid motors at the desired times in the operating cycle to affect both operating and return movements of the several motors. The outlet end of the valve shaft carries a Geneva drive motion including a rotating collar 51 having an eccentric pin thereon for cooperation with spaced notches in a disc 52. The disc 52 is connected to one of the sprockets carrying the conveyor chains so that the conveyor will be fed intermittently.

The operating cycle of the machine is illustrated in Figure 2. In the position of the parts at the top of the diagram a primer body has just been fed into register with the guide collar 23 and a liner tube has just been fed onto the trough 21. At this point, fluid is admitted to the lower end of the cylinder 36 to advance the head 37 which engages the lower end of the primer body and forces the primer body into the head as shown

in Figure 7. This is indicated by the outer-most line starting at the top of the vertical line and continuing to the bottom of the vertical line throughout 180° of the cycle. This indicates that the motor 36 remains energized to hold the primer body against the head during this portion of the cycle.

The next step in the operation is the advancing of the liner plunger 29 which starts after the primer body has been seated against the head as indicated by the next line at the left of the diaphragm. As this plunger advances it engages the diaphragm on the liner tube and forces the tube and diaphragm through the opening 24 into the primer body to the desired depth as determined by the stop pin 32. When this operation is completed, fluid is admitted to the left end of the cylinder 45 to advance the piston 43 to inject paint or other sealing material around the periphery of the diaphragm. This operation is indicated by the short line adjacent the bottom of the diaphragm.

Upon completion of the paint injecting operation the fluid connections to the piston 34 and 36 are reversed to retract the plunger and the head 37. When this is done, the primer body with the liner assembled therein and with sealing material applied will drop away from the head 23 onto the conveyor. At this point the conveyor will be advanced through the Geneva motion to bring the next primer body into alignment with the head 23 and the motor 22 will be actuated to feed the next liner onto the trough 21. The cycle is then completed, ready for a repetition of the operation.

As the primer bodies are carried away from the frame by the conveyor they will rest on the rails 16 and will accordingly be rotated about their own axis while being held at an angle to the horizontal. This operation will distribute the sealing material uniformly around the periphery of the diaphragms so that by the time the primers are discharged from the conveyor the diaphragms will be sealed completely around their periphery ready for a subsequent drying operation.

In addition to assembling percussion primers of the specific type described above, the machine of the present invention may also be used to assemble primers of the type in which no diaphragm intermediate the ends of the primer body is employed. In this type of construction a liner tube is inserted in the primer body with its closed end lying adjacent the closed end of the body and the openings in the body are sealed by the application of paint or like sealing material. It has been found in this type of assembly that leakage is apt to occur around the plug threaded into the end of the body and it is important that this plug be sealed in order to prevent such leakage. For this purpose the plunger 29 may be forced into the primer body completely to the end thereof without any liner in the body and a charge of sealing material may be forced through the plunger to seal around the periphery of the threaded plug. Thereafter the liner may be inserted by a similar plunger which in this case need not be hollow. It will be understood that these two operations can be separately performed on different machines or that, if desired, two heads might be provided on the same machine to perform a two-stage operation.

While one embodiment of the invention has been shown and described in detail, it will be un-

derstood that this embodiment is illustrative only and is not intended as a definition of the scope of the invention, reference being had for this purpose to the appended claims.

What is claimed is:

1. Apparatus for assembling percussion primers comprising a head having an opening therethrough, means for holding a tubular primer body against the head in register with one end of the opening, a plunger adapted to pass through the opening to force a liner tube into the body, the plunger being hollow and having a discharge opening at its outer end, means to advance the plunger, and means to force sealing material through the discharge opening after the plunger has been advanced.

2. Apparatus for assembling percussion primers comprising a head having an opening therethrough, means for holding a tubular primer body against the head in register with one end of the opening, a plunger adapted to pass through the opening to force a liner tube into the body, the plunger being hollow and having a discharge opening at its outer end, a piston slidable in the plunger to force a measured quantity of sealing material through the discharge opening, means to advance the plunger, and means for thereafter moving the piston to feed the sealing material.

3. Apparatus for assembling percussion primers comprising means for supporting a tubular primer body at an acute angle to horizontal, means for forcing a tubular liner down into a primer body supported by the first-named means, means for supplying sealing material to the upper end of the liner after it has been forced into the primer body, and means for rotating the primer body with the liner and sealing material therein while maintaining it at an angle to horizontal.

4. Apparatus for assembling percussion primers comprising means for supporting a tubular primer body at an acute angle to horizontal, means for forcing a tubular liner down into a primer body supported by the first named means, with a substantially flat sealing diaphragm on top of the liner, means for depositing a small quantity of sealing material at the periphery of the diaphragm after it has been forced into the primer body, and means for rotating the body with the diaphragm and sealing material therein while maintaining it at an angle to horizontal to distribute the sealing material around the periphery of the diaphragm.

5. Apparatus for assembling percussion primers comprising a head having an opening therethrough, a conveyor for moving tubular primer bodies successively into register with the head, means for moving and holding a primer body registering with the head against the head at one end thereof, means for successively feeding liner tubes into register with the other end of the head, means including a plunger for forcing the liner tubes through the head into the primer bodies, and control means for actuating the conveyor, the moving and holding means, the tube feeding means and the plunger in timed relation.

6. Apparatus for assembling percussion primers comprising a head having an opening therethrough, a conveyor for moving tubular primer bodies successively into register with the head, means for moving and holding a primer body registering with the head against the head at one end thereof, means for successively feeding liner

tubes into register with the other end of the head, means including a plunger for forcing the liner tubes through the head into the primer bodies, means cooperating with the plunger to feed a small quantity of sealing material therethrough at the end of the forcing stroke of the plunger, and control means for actuating the conveyor, the moving and holding means, the tube feeding means, the plunger and the sealing material feeding means in timed relation.

7. Apparatus for assembling percussion primers comprising a head having an opening therethrough, a conveyor for moving tubular primer bodies successively into register with the head, means for moving and holding a primer body registering with the head against the head at one end thereof, means for successively feeding liner tubes into register with the other end of the head, means including a plunger for forcing the liner tubes through the head into the primer bodies, means cooperating with the plunger to feed a small quantity of sealing material therethrough at the end of the forcing stroke of the plunger, a continuously operating motor, intermittent drive means operated by the motor to drive the conveyor, and control means operated by the motor for actuating the moving and holding means, the tube feeding means, the plunger and the sealing material feeding means in timed relation with the conveyor.

8. Apparatus for assembling primer bodies comprising a head having an opening therethrough, a conveyor for successively moving tubular primer bodies into register with the head, power means for intermittently driving the conveyor, a fluid motor for moving and holding the primer bodies against one end of the head, means for feeding liner tubes into register with the other end of the head, a fluid motor for actuating the liner tube feed, a plunger to force the liner tubes through the head into the primer bodies, a fluid motor to operate the plunger, and a control valve operated by the power means to actuate the fluid motors in timed relation.

9. Apparatus for assembling primer bodies comprising a head having an opening therethrough, a conveyor for successively moving tubular primer bodies into register with the head, power means for intermittently driving the conveyor, a fluid motor for moving and holding the primer bodies against one end of the head, means for feeding liner tubes into register with the other end of the head, a fluid motor for actuating the liner tube feed, a plunger to force the liner tubes through the head into the primer bodies, a fluid motor to operate the plunger, a second plunger cooperating with the first plunger to feed a small amount of sealing material therethrough, a fluid motor for operating the second plunger, and a control valve operated by the power means to actuate the fluid motors in timed relation.

10. In an apparatus for assembling percussion primers, means for forcing liners into tubular primer bodies comprising a reciprocable plunger, the plunger being hollow and having a peripheral outlet opening at its outer end, means to supply sealing material to the plunger, a piston slidable in the plunger to force sealing material through the outlet opening, and a motor reciprocable with the plunger and connected to the piston to operate it.

11: In an apparatus for assembling percussion primers, means for forcing liners into tubular primer bodies comprising a reciprocable plunger,

the plunger being hollow and having a peripheral outlet opening at its outer end, means to supply sealing material to the plunger, a piston 5 slideable in the plunger to force sealing material through the outlet opening, a cylinder reciprocable with the plunger, a piston in the cylinder connected to the first named piston, and flexible conduits to supply operating fluid to the cylinder.

12. In an apparatus for assembling percussion primers, means for forcing liners into tubular primer bodies comprising a reciprocable plunger, the plunger being hollow and having a peripheral outlet opening at its outer end, means to supply sealing material to the plunger, a piston 15 slideable in the plunger to force sealing material through the outlet opening, a block connected to the plunger and reciprocable therewith, a fluid motor connected to the block to reciprocate it, a fluid motor carried by the block and connected to the piston, and a control valve to control operation of the fluid motors in timed sequence.

13. In a machine for assembling percussion primers, a head having an opening therethrough, means to hold a tubular primer body against the head in register with one end of the opening, a plunger, means to force the plunger through the head into the primer body, the plunger having 25 openings therein terminating adjacent its periphery at its outer end, and means to force a charge of sealing material through the openings to form 30 a seal in the primer body.

14. Apparatus for assembling percussion primers comprising a frame lying at an acute angle

to the horizontal, means for carrying tubular primer bodies across the frame at the same angle as the frame, means on the frame to insert a liner tube and a small quantity of sealing material into the primer bodies as they cross the frame, and supporting bars upon which the bodies roll as they leave the frame so that the bodies will be rotated to distribute the sealing material therein.

15. Apparatus for assembling percussion primers comprising a frame lying at an acute angle to the horizontal, means for carrying tubular primer bodies across the frame at the same angle as the frame, means on the frame to insert a substantially flat diaphragm and a small amount of sealing material into each body as it registers with the frame, and means cooperating with the bodies as they move away from the frame to rotate them to distribute the sealing material around the periphery of the diaphragm.

16. Apparatus for assembling percussion primers comprising a frame lying at an acute angle to the horizontal, means for carrying tubular primer bodies across the frame at the same angle as the frame, means on the frame to insert a substantially flat diaphragm and a small amount of sealing material into each body as it registers with the frame, and bars underlying the carrying means and upon which the bodies roll as they move away from the frame to distribute the sealing material around the periphery of the diaphragm.

SIDNEY E. VAN TUYL.
